United States Patent Office

Des. 188,255
Patented June 21, 1960

188,255

SOCK

Alcide O. Cormier, Laconia, N.H., assignor to Roland J. G. Nadeau, Laconia, N.H., as trustee

Filed Sept. 28, 1959, Ser. No. 57,713

Term of patent 14 years

(Cl. D47—7)

The figure is a side elevational view of a sock showing my new design, the opposite face being identical with the face shown.

I claim:

The ornamental design for a sock, substantially as shown and described.
